Primary Examiner — Janice Hallmark(74) *Attorney, Agent, or Firm* — Renner, Otto, Boisselle & Sklar, LLP(57) **CLAIM**

The ornamental design for a fan with integral airflow guide, as shown and described.

DESCRIPTION

The FIGURE is a top plan view of a fan with integral airflow guide showing my new design.

The surfaces or portions of the fan with integral airflow guide that are not shown in the FIGURE or described in the specification form no part of the claimed design. The broken line showing in the FIGURE is for the purpose of illustrating portions of the fan with integral airflow guide and forms no part of the claimed design.
